CLAIM

The ornamental design for a trunk, as shown and described.

DESCRIPTION

FIG. 1 is a perspective view of the trunk showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof;

FIG. 9 is a bottom perspective thereof;

FIG. 10 is a bottom perspective view thereof;

FIG. 11 is a perspective view of the trunk in another embodiment;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof;

FIG. 18 is a perspective view thereof;

FIG. 19 is a bottom perspective thereof; and,

FIG. 20 is a bottom perspective view thereof.

The dash-dash broken lines depict portions of the trunk that form no part of the claimed design.

1 Claim, 20 Drawing Sheets
